UNITED STATES PATENT OFFICE.

FRANK L. BETTS, OF UNIVERSITY CITY, MISSOURI.

TUBE CONTAINER AND CLOSURE THEREFOR.

Application filed October 9, 1926. Serial No. 140,554.

My invention relates to tube containers and closures therefor and more particularly to tube containers which are collapsible and are otherwise adapted to be filled with plastic material such as cream, paste, paint, shaving and dental cream and ointment.

Heretofore such tubes have usually been provided with a cover threaded on the upper end of the neck of the tube and when it was desired to use some of the material contained in the tube the cover had to be unscrewed from the neck before the material could be expelled from the tube and after the required amount of material had been obtained it was necessary to screw the cap back on the tube to keep the material remaining in the tube from being hardened or otherwise rendered unfit for use by contact with the air. Tube containers were necessarily of cheap construction and therefore after the caps have been removed and replaced on the tube a number of times the threads often became damaged and prevented the cap from being properly screwed on the tube. Also, the caps were often lost.

Several attempts have been made to provide a closure for tube containers which would obviate these difficulties but in each case the closures were usually too expensive to manufacture and assemble or were inoperative when repeatedly used and therefore were commercially impractical.

The objects of my invention are to provide a tube container with a closure therefor which will be inexpensive to manufacture and to provide a tube container with a closure therefor which may be easily and quickly operated to open the tube to allow material therein to be expelled therefrom or be operated to close the tube.

With these and other objects in view one embodiment of my invention is fully shown in the accompanying drawings wherein Fig. 1 is a top view of the tube container with the closure therefor; Fig. 2 is a side view; Fig. 3 is a top view of the tube with the closure removed; Figs. 4 and 5 are sections along the lines 4-4 in Fig. 1 and with the valve member of the closure in open and closed positions, respectively; and Fig. 6 is a view of the valve member.

Referring to the figures, the collapsible tube 1 has formed on the upper end thereof a neck 2, which in this form of my invention has a substantially hemi-spherical depres-

sion 3 formed in the upper end thereof, as fully shown in Fig. 3, and has, preferably at the bottom of the depression 3, a discharge opening 4 leading from the interior of the tube. Seated in the depression 3 is a valve member 5, preferably substantially spherical in shape, as shown in detail in Fig. 6, and which has a channel 6 cut inwardly from the outer surface thereof to extend as shown in Fig. 4 between nearly diametrically opposite points on the valve member. The valve member 5 has a projection 7 extending outwardly therefrom and adapted to pass through the slot 8 cut in the cover 9. The cover 9 has the inner surface thereof formed to substantially follow the contour of the upper part of the valve member 5 and is otherwise adapted and arranged so that when in place it will maintain the valve member on its seat in the depression 3. The cover 9 and the neck 2 are, preferably, threaded so that the cover may be screwed onto the neck.

I prefer that the channel 6 shall extend from a point near the projection 7 and be arranged substantially in line circumferential- 80 with the projection as shown in the figures, and that side walls of the slot 8 each lie in a plane substantially parallel with the vertical axis of the cover 9 for the purposes more fully hereinafter set forth.

In assembling the tube container and the closure the valve member 5 is seated in the depression 3 with the projection 7 of the valve member extending upwardly. The cover 9 is placed so that the projection 7 extends through the slot 8 and the cover is screwed onto the neck 2. Since the projection 7 extends through the slot 8 the valve member 5 will be turned with the cover when the latter is being screwed in place. The cover 9 is screwed down until the valve member 5 is in proper position on its seat. The cover may be adjusted on the threaded portion of the neck 2 to allow for slight differences in size of the valve member 5.

The operation of my device is as follows:— When it is desired to expel material from the tube 1, the projection 7 is moved until it is at the inner end of the slot 8, as shown in Fig. 4, when the channel 6 will provide a passage from the discharge opening 4 to the slot 8. When enough material has been expelled from the tube and it is desired to close the tube, the projection 7 is moved to the other or outer end of the slot 8 thereby moving

the valve member 5 into the position shown in Fig. 5 and the passage is thereby closed. I prefer that the projection 7 have two flat sides which bear against the side walls of the 5 slot 8, as shown in Fig. 1, so that the valve member 5 is movable only in a direction substantially parallel with the side walls of the slot 8, and no other turning movement of the valve will be allowed. Also if the valve and 10 the cover 9 are formed as described and shown and the movement of the valve is always in a plane substantially parallel to the side walls of the slot 8, when the projection 7 is moved in the slot 8 there will be no tendency 15 for the movement to turn the cover and thereby to unscrew or to tighten the cover 9. Further, with the channel 6 and the projection 7 arranged in relation with one another as described and shown, when the passage 20 between the openings 4 and 8 is closed the valve member will be moved to bring the channel downwardly into the depression 3 and, therefore, the edge formed by the bottom 25 wall of the channel and the adjacent surface of the valve member near the projection 7 will act as a cutting edge to cut off the material that has already been expelled through the slot 8.

It will be readily understood that I do not 30 propose to limit my invention to the exact details of construction shown in the drawings and described above since the parts may be changed in size and shape within wide limits without deviating from the spirit of 35 my invention as included in the claims below. For instance, the valve member 5 may be in the shape of a segment of a sphere rather than a sphere as shown. Likewise, in some cases the valve member 5 may be provided 40 with an opening therethrough rather than the channel 6 cut inwardly from the surface thereof.

What I claim as new and desire to secure by 45 Letters Patent, is:—

1. The combination with a tube container 50 having a neck provided with a discharge opening therethrough, of a closure therefor comprising a cover engaging said neck and having an elongated opening therein, a valve 55 member movably mounted between said cover and said neck and having a projection extending therefrom through said opening in said cover, said valve member having a channel 60 therein and being formed and arranged to be movable by a movement of said projection into a position whereby said channel will provide a passage from said opening in said neck to the opening in said cover through which material contained in said tube may 65 be expelled therefrom, said valve member also being movable into a position to prevent the expulsion of said material and said elongated opening in said cover being positioned and arranged whereby when said projection 70 is moved in said opening the side walls of

said opening will guide said projection to move said valve into one of said positions.

2. The combination with a tube container 70 having a neck provided with a discharge opening therethrough, of a closure therefor comprising a cover engaging said neck and having a slot therein, a valve member seated between said cover and said neck and having a projection extending therefrom through said slot in said cover, and said valve member 75 having a channel therein and being formed and arranged so that when said projection is moved to one end of said slot said valve member is moved into a position whereby said channel will provide a passage from said opening in said neck to the slot in said cover through which material contained in said tube may be expelled therefrom, and said valve member 80 also being formed and arranged so that when said projection is moved to the other end of said slot said valve will be moved into a position to prevent expulsion of said material.

3. The combination with a tube container 85 having a neck provided with a discharge opening therethrough of a closure therefor comprising a cover threaded on said neck and having an elongated opening therein, a valve member 90 movably mounted between said cover and said neck and having a projection extending therefrom through said opening in said cover, said valve member having a channel therethrough and being formed and arranged to be movable by a movement of said projection into a position whereby said channel will 95 provide a passage from said opening in said neck to the opening in said cover through which material contained in said tube may be expelled therefrom, and said valve member 100 also being movable into a position to prevent the expulsion of said material, and said projection and said elongated opening being arranged so that said projection is movable only 105 in a plane substantially parallel to the axis of said cover.

4. The combination with a tube container 110 having a neck provided with a discharge opening therethrough and having a substantially hemi-spherical depression extending inwardly from the upper end thereof, of a closure therefor comprising a substantially spherical valve member seated in said depression, a cover having the inner surface 115 thereof arranged to follow the contour of said valve member and otherwise adapted to maintain said valve member on its seat, said cover having a slot therein and said valve member having a projection extending through said slot, and said valve member having a channel 120 therein and being formed and arranged so that when said projection is moved to the inner end of said slot said valve member is moved into a position whereby said channel will provide a passage for the expulsion of 125 material from said tube and said valve also 130

being formed and arranged so that when said projection is moved to the outer end of said slot said valve member will prevent the expulsion from said tube of said material.

5. 5. The combination with a tube container having a neck provided with a discharge opening therethrough and having a substantially hemi-spherical depression extending inwardly from the upper end thereof, of a closure therefore comprising a substantially spherical valve member seated in said depression, a cover having the inner surface thereof arranged to follow the contour of said valve member and being threaded on said neck, said cover having a slot therein whose side walls extend in a plane substantially parallel to the axis of said cover, said valve mem-

ber having a projection extending therefrom through said slot, and said valve member also having a channel in the surface thereof extending between nearly diametrically opposite points and arranged whereby when said projection is moved to the inner end of said slot said channel will extend from the opening in said neck to the slot in said cover to provide a passage through which material contained in said tube may be expelled therefrom and whereby when said projection is moved to the outer end of said slot expulsion of said material will be prevented.

In witness whereof I have signed my name to the foregoing specification.

FRANK L. BETTS.
